Albert Edward Hawkins, Ottawa,
Ontario, CanadaApplication April 14, 1947, Serial No. 138,397
In Canada November 6, 1946

Term of patent 14 years

(Cl. D85—2)

To all whom it may concern:

Be it known that I, Albert Edward Hawkins, a subject of the King of Great Britain, residing in the city of Ottawa, Province of Ontario, Dominion of Canada, have invented a new, original, and ornamental Design for a Container for Cigarettes and Like Cylindrical Objects, of which the following is a specification, reference being had to the accompanying drawing, forming part thereof.

In the drawing:

Figure 1 is a top plan view; and

Figure 2 is a perspective view of the container for cigarettes and like cylindrical objects, showing my new design.

I claim:

The ornamental design for a container for cigarettes and like cylindrical objects, as shown.
ALBERT EDWARD HAWKINS.
